UNITED STATES PATENT OFFICE.

NICHOLAS PISCIONEREE, OF SOUTH WEYMOUTH, MASSACHUSETTS.

ELECTRIC HAMMER AND DRILL.

Application filed March 12, 1925. Serial No. 14,993.

This invention relates to improvements in electric hammers and drills and its main object is to provide an electric hammer having means incorporated therein for rotating the tool holder, thereby making it adaptable for drilling purposes and general millwright work.

Another object is to provide in combination with the hammer a device for automatically regulating and controlling the electric current and wherein means are devised for short circuiting the current in case of an overload, and for breaking the short circuit when the excessive load has been eliminated. 15 These and other objects will be apparent from the accompanying drawings and specification.

In the drawings:

Figure 1 is a top plan view of the hammer;

Figure 2 is a bottom plan view of the hammer;

Figure 3 is a longitudinal section taken on the line "3—3" of Figure 1;

Figure 4 is a longitudinal section taken on the line "4—4" of Figure 1;

Figure 5 is a transverse section taken on the line "5—5" of Figure 3;

Figure 6 is a transverse section taken on the line "6—6" of Figure 3;

Figure 7 is a detail of the current reversing contacts;

Figure 8 is a diagram showing the travel of the piston in the hammer, the piston being directed downward.

In carrying out this invention I provide a split insulated field casing 1 having lugs 2 incorporated therein to permit securing the parts of the casing 1 together by means of bolts as shown at 3. The field casing 1 has a series of grooves 4 cut therein in order to permit the mounting of a field winding 5. The said field winding 5 is held in place within the casing 1 by means of copper strips 6 which are secured in dove-tail grooves 7. A rectangular groove 8 which is lined with insulating material is cut longitudinally in the inner face of the field casing 1 and the connecting wires of the coils which compose the field winding 5 are passed therethrough. A commutator bar 9 which carries the field winding coil connecting wires is mounted in the insulated rectangular groove 8 in such a manner that its face is flush with the inner face of the field casing 1. The upper portion of the

field casing 1 is enlarged relative to the lower portion to such an extent as to form a substantial shoulder 10 upon which a buffer plate 11 is mounted. A coil spring 12 which serves the purpose of a shock absorber for the piston 17 and is mounted upon the buffer plate 11 is adapted to engage a disc 13 which is threaded secured in the field casing 1. A steady post 14, corresponding in cross-section to a quadrate cross, is passed through the casing and secured to the said disc 13. Conductors 15 and 16 are secured in and insulated against the steady post 14. A piston 17 having a quadrate aperture complementary to the steady post 14, and which is adapted to travel the length of the field winding 5 is slidingly mounted upon the steady post 14 and has a peripheral groove 18 cut therein in which a magnetic coil 19 is mounted. Brush cylinders 20 which have the ends of the coil 19 secured thereto are insulated against and secured in the piston 17. Springs 21 and brushes 22 are mounted in the brush cylinders 20 and are adapted to engage the conductors 16 which are secured in the steady post 14. A cylinder 23 which is insulated against and secured in the piston 17 carries a spring 24 and brushes 25; the said brushes 25 being adapted to engage the conductors 15 and the commutator bar 9. Contact straps 26 and 27 and segments 28 and 29 are insulated against and secured to the upper inner face of the field casing 1. The ends of the field winding 5 and the segments 28 are connected with suitable wiring 30, while suitable wiring 31 connects the conductor 15 with the segment 29, and suitable wiring 32 connects one of the conductors 16 with the contact strap 27, while the other conductor 16 is connected with the negative power line. Cam apertures 34 are cut in the field casing 1 at each end of the field winding 5, while cams 35 are passed therethrough and secured to a shaft 36 which is longitudinally journaled to the field casing 1 by means of bearings 37. The cams 35 have their inner faces 38 cut at such an angle that their alternate engagement with the ends of the piston 17 will cause the said cams 35 to traverse an angle of approximately 10 degrees. A brush arm aperture 39 is cut in the upper portion of the field casing 1 in line with the cam apertures 34 and a brush arm 40 is passed therethrough and secured to the shaft 36. Brush fingers

41 and 42 carrying spring set brushes 43 and 44 respectively are insulated against and secured in the brush arm 40. The upper brush 43 of the finger 41 engages the contact strap 26 while the lower brush 43 of the said finger 41 is adapted to alternately engage one of the segments 28 and the segment 29, while the upper brush 44 of the finger 42 engages the contact strap 27, and the lower brush 44 of the said finger 42 alternately engages the segment 29 and one of the segments 28. It will be noted that when the south pole of the piston engages the lower cam 35, the brush arm 40 is shifted so that the brushes 43 of the finger 41 engage the contact strap 26 and the segment 28, while the brushes 44 of the finger 42 engage the contact strap 27 and the segment 29. When the north pole of the piston engages the upper cam 35, the arm 40 is shifted so that the brushes 43 of the finger 41 engage the contact strap 26 and the segment 29, while the brushes 44 of the finger 42 engage the contact strap 27 and the segment 28. An insulated cap 45 carrying an end bearing 46 in which the one end of the shaft 36 is journaled is secured to the top of the field casing 1. An end spacer 47 having pawl apertures 48 and 49 cut therein is threadedly secured to the lower end of the field casing 1. A spring set pawl 50 is mounted in the pawl aperture 48. An arm 51 which extends into the pawl aperture 49 and carries a spring set pawl 52 is secured to the shaft 36. A tool holder 53 has a head 54 which slidingly engages the field casing 1 and the end spacer 47, incorporated therein. The pawls 50 and 52 are adapted to engage ratchet teeth 55 which are cut in the head 54 so that every time the north pole (N. P.) of the piston 17 engages the cam 35 the tool holder 53 is rotated a trifle. An end plate 56 carrying a buffer 57 is threadedly secured to the end spacer 47. The said buffer 57 is provided to absorb the shock of the piston 17 when running idle. An end bearing 58 in which the lower end of the shaft 36 is journaled is secured to the end plate 56. A guard 59 is placed over the shaft 36 and secured to the field casing 1, the cap 45 and the end plate 56. A handle plate 60 having the lower half 63 of a switch 62 incorporated therein, is secured to the cap 45. A spring set handle 61 having the upper half 64 of the switch 62 incorporated therein, is hingedly secured to the handle plate 60. The lower half 63 of the switch 62 is connected with the contact strap 26 by means of suitable wiring 65, while the upper half 64 is connected with suitable wiring 66.

Reference being had more particularly to the diagrammatic Figure 8, the operation is as follows: When the switch 62 is closed, the current flows through the wiring 65 into the contact strap 26 whence it passes

through the brushes 43 and brush finger 41 into the segment 28 which is connected to the field winding 5 by means of a split wiring 30 which causes half of the current to enter the said field winding from the top 70 and the other half from the bottom. From the segment 29 the current travels through the finger 42 and brushes 44 into the contact strap 27, through the contact strap 27 and the wiring 32 into one of the conductors 75 16, then through one of the brushes 22 into the coil 19 and then through the other brush 22 into the conductor 16 which is connected with the negative power line 33, thus completing the circuit.

As shown in the diagrammatic Figure 8 magnetic fields of opposite polarity enter and leave the field winding 5 above and below the piston during its reciprocation, and thus exert on it simultaneously, a pushing 80 and pulling force. When the piston 17 reaches the top of the field winding 5 it engages the upper cam 35 and causes the shaft 36 to be partially rotated to the right, thereby shifting the brush arm 40 and causing the current to be reversed, at the same time moving the pawl into position for the partial rotation of the tool holder 53 upon the downward stroke of the piston 17. When the brush arm 40 is shifted to the right, as 85 shown in Figure 8, the connections between the contact strap 26 and segment 28 and the contact strap 27 and segment 29 are broken, while connections are formed between the contact strap 26 and segment 29, and the contact strap 27 and segment 28. When the connections are so made the current passes through the negative line 33 into one of the conductors 16, through the brush 22 into the piston winding 19, then through the other brush 22 into the other conductor 16 and then through the wiring 32 into the contact strap 27. From the contact strap 27 the current passes through the brushes 44 and finger 42 into the segment 28, then through the wiring 30 into the field winding 5, where the magnetic lines of force created by the field winding 5 pass into the commutator bar 9 then through the brushes 25 into the conductor 15 and then through the wiring 110 31, the brushes 43 and finger 41, into the contact strap 26. When shifting the brushes into the position shown in Figure 8, the magnetic lines of force are reversed so that the piston 17 will be hurled down 115 upon the head 54 of the tool holder 53. Just before the piston is hurled upon the tool holder it engages the lower cam 35 and causes the same to partially rotate the shaft 36 to the left, thereby causing the arm 51 120 carrying the pawl 52 to partially rotate the tool holder 53. The said shaft 36 also shifts the brush arm 40 into its former position for reversing the current for the up stroke 125 of the piston.

While I have herein described a certain specific method of constructing and assembling the elements of my invention, it is understood same may be varied in minor details, not departing from the spirit of my invention as defined in the appended claims.

I claim:

1. In an electric hammer embodying a split field casing, a field winding in the casing, a wound reciprocating piston within the casing, a tool holder in the lower end of the casing, electric switches and reversing elements in said casing; a steadyng post, corresponding to a quadrate cross in cross section, mounted longitudinally through the center of the casing, and upon which the said piston is slidngly mounted; means in the casing for absorbing the shock of the upward movement of the reciprocating piston; a tool holder adapted to be engaged by the piston in the lower portion of said casing; and means for rotating the tool holder thru the reciprocating movement of said piston.
2. In a device of the kind described, embodying a split field casing, the said casing having a commutator bar slot cut longitudinally along its inner surface, a field winding in the casing, a wound piston within the casing, a tool holder at the lower end of the casing, and electric switches and reversing elements in said casing; a commutator bar mounted within the said slot of the casing, as means for leading the current from the field winding of the casing through the switches into the piston winding; a shaft

vertically journaled to the side of said casing; current reversing brushes secured to the upper end of said shaft; and means secured to said shaft and passed thru the side of said casing for rotating the tool holder thru the reciprocating movement of said piston.

3. In a device of the kind described, embodying a casing having a brush arm aperture cut through the wall of the upper end, and having two cam apertures cut through the casing wall in longitudinal alignment with the said brush arm aperture, one of the said cam apertures being located at the lower end of the casing and the other medially between the lower cam and the said brush arm aperture; a shaft journaled longitudinally at the outer face of the casing opposite the said cam and brush arm apertures; a brush arm mounted through the said brush arm aperture and connected to the shaft; reversing cams mounted through the cam apertures and connected to the shaft; brushes mounted at the inner end of and insulated against the said brush arm; segments and contacts mounted in and insulated against the casing and adapted to cooperate with the said brushes for controlling the electric current.

4. In a device as described in claim 3 shock absorbing means in said casing for absorbing the power of the upward movement of the reciprocating piston.

In testimony whereof I affix my signature.

NICHOLAS PISCIONERE.
